UNITED STATES PATENT OFFICE.

GEORGE LANE, OF POUGHKEEPSIE, NEW YORK.

LIFTING-JACK.

SPECIFICATION forming part of Letters Patent No. 539,956, dated May 28, 1895.

Application filed March 8, 1895. Serial No. 541,032. (No model.)

To all whom it may concern:

Be it known that I, GEORGE LANE, a citizen of the United States, residing at Poughkeepsie, in the county of Dutchess and State of New York, have invented certain new and useful Improvements in Lifting-Jacks, of which the following is a specification, reference being had therein to the accompanying drawings.

10 It is the object of my invention to provide a lifting jack for wagons and carriages of simple and economical construction and which while requiring a minimum amount of material will have the highest degree of strength necessary to durability and efficiency.

15 My invention comprises a lifting bar having a lifting foot and carried by a pair of links pivoted to a standard; a lifting lever pivoted to the said lifting bar and fulcrumed upon a 20 swinging link which in turn is pivoted to the lower carrying link, the said standard being formed of two side sections or plates between which the lifting bar and lever and the links extend, being guided and maintained laterally thereby, the said lifting bar being maintained in vertical position also by the pair of carrying links.

25 In the drawings, Figure 1 is a perspective view of the invention with the lifting-bar down. Fig. 2 is a side view with the lifting-bar up. Fig. 3 is a plan view. Fig. 4 is a perspective view of the jack with one side of the standard removed.

30 The lifting bar consists of two comparatively thin flat bars 1, 1, arranged with a space between them, their upper ends being connected through a space block 3, while their lower portions receive between them the links and lever hereinafter mentioned. The rear 35 edges of the plates forming the bar are serrated to hold adjustably the lifting foot 4' which extends between the parts of the bar and has a pin on its rear portion engaging the serrations. A binding pin bears on the front 40 side of the bar and thus the foot may be fixed at any height on the bar. A stop pin 9 limits the tilting or tipping movement of the foot. The bar is carried by a pair of links 4, 5, pivoted to the standard 6 at or near the rear edge 45 thereof. The free ends of these links extend between the sides of the lifting bar and are pivoted thereto. The lifting lever 12 is also 50

55 pivotally connected between the sides of the lifting bar and extends rearwardly and curving upward therefrom terminates in a suitable handle. This lever is fulcrumed on the upper end of a swinging link 7 the lower end of which is pivoted to the rear arm or extension of the lower carrying link. By reason of this arrangement, the lifting lever at its 60 front end will exert its lifting power directly on the bar and the pressure of the lever on its fulcrum will also be transmitted to the bar as a lifting force through the swinging fulcrum link and the lower carrying link. The 65 arrangement of the parts is also such that when the load is lifted and the lifting lever is down the fulcrum of the lever will be thrown below a line drawn between the pivot of the lever and the pivot of the swinging fulcrum 70 link and the parts will thus be locked to hold the load raised.

75 The pair of carrying links, when the lifting bar is at half stroke, extend substantially horizontally, and they move from this position equally when operated up or down. When the bar is down, the lifting lever is upright, extending close to the bar and forming a compact arrangement, and when the jack is operated to the full stroke, the lifting lever is in 80 substantially horizontal position from the standard outward, the inner end curving upward within the standard to its point of connection with the lifting bar. The curved part of the lever finds a stop against the upper 85 edge of the lower carrying link.

90 The standard is made up of two side pieces or flat plates having laterally extending foot portions 10 secured to a suitable base. The side pieces are made broad and the lifting bar 95 is arranged between the front edges thereof so that the bar is guided in its vertical movement and is securely maintained against lateral play. The upper and lower carrying links insure the vertical direction of the bar's 100 movement and maintain it securely against displacement toward the front or rear. These carrying links are themselves arranged, together with the lifting lever, in between the sides of the standards, and all of these parts are held against lateral displacement by the standard.

105 The swinging fulcrum link is made up of two sides embracing the lifting lever, and the

end of this link works in between the sides of the standard when the jack is operated.

I claim as my invention—

1. A lifting jack comprising a standard, a lifting lever, a lifting bar, a swinging fulcrum link for the lifting lever and a pair of links connected with the lifting bar to maintain the same in vertical position, the said fulcrum link being connected with the lifting lever and with one of the pair of links the other link being independent of the lifting lever and connecting the lifting bar with the standard substantially as described.
2. A lifting jack comprising a standard, a lifting bar, a lifting lever pivotally connected therewith, a link pivoted to the upper end of the standard and to the lifting bar, a lower link pivoted to the lower part of the standard and to the lifting bar, a fulcrum link extending between the lifting lever and the lower link, said lower link having a rear extension and the said lifting lever operating between the upper and lower links substantially as described.
3. In combination, the standard comprising the two sides, the lifting bar also composed of two sides with a space between said lifting bar being guided between the sides of the standards at or near one edge thereof and means for lifting and controlling the bar said means comprising a link or links pivoted between the sides of the lifting bar and extending between the sides of the standards and pivoted at or near the opposite edge thereof, a lifting lever also pivoted between the parts of the lifting bar and extending between the standard sides and a fulcrum for said lever, substantially as described.

4. In combination, the standard comprising the two sides, a lifting bar guided vertically between the sides of said standard at or near one edge thereof and lifting means for the lifting bar said means comprising the link or links pivoted thereto and extending between the sides of the standard and pivoted at or near the opposite edge of the said sides, a lever pivoted to the lifting bar and also extending between the standard sides and a fulcrum for said lever, substantially as described.

5. A lifting jack comprising a standard, a lifting bar, a lifting lever pivotally connected therewith, the upper and lower carrying links, both connecting the lifting bar with the standard the swinging fulcrum link pivoted to the lifting lever and to a rear extension of the lower carrying link, the said fulcrum link being arranged to swing forward beyond the line drawn through the pivotal connection of the lever with the lifting bar and the rear pivotal connection of the fulcrum link with the lower carrying link to lock the parts in raised position, substantially as described.

6. In combination, the standard, the lifting bar, the upper and lower carrying links pivoted to the standard and to the lifting bar, the lifting lever, the fulcrum link pivoted thereto and to the rear extension of the lower carrying link, the said lifting lever being arranged to abut against the said rear extension and with the fulcrum link to lock the parts.

In testimony whereof I affix my signature in presence of two witnesses.

GEORGE LANE.
